Patented Dec. 18, 1917.

UNITED STATES PATENT OFFICE.

CLARENCE D. PLATT, OF BRIDGEPORT, CONNECTICUT.

ELECTRIC SWITCH.

1,250,501.

Specification of Letters Patent. Patented Dec. 18, 1917.

Application filed August 2, 1916. Serial No. 112,710.

To all whom it may concern:

Be it known that I, CLARENCE D. PLATT, a citizen of the United States of America, residing at Bridgeport, Fairfield county, Connecticut, have invented a new and useful Electric Switch, of which the following is a specification.

My invention relates to electric switches, and among my chief objects are simplicity 10 of construction, durability and effectiveness of operation. My improved switch while unlimited in its field of usefulness, is of particular value when employed as an entrance switch, such as used for house lighting service. In its preferred form, shown and described herein, it is so arranged as to be protected by box and cover, and in order to simplify the construction and eliminate unnecessary parts, I utilize the box cover as the 15 switch handle. The switch is of the so-called blade type, but instead of being slow acting, I have so constructed the parts, that the separation of the blade from its contact or contacts is so quickly effected as to prevent arcing.

In the drawings:

Figure 1 is a front view of a switch terminal box constructed to embody my improved switch, the cover of the box and the 20 switch element carried thereby being fully opened.

Fig. 2 is a side elevation partly broken away and in section on the line 2—2 of Fig. 1.

Fig. 3 is a section on the plane of the line 3—3 of Fig. 1, showing the cover closed and the switch on, or in the circuit closing position.

Fig. 4 is a cross section on the plane of the line 4—4, Fig. 1.

In that form of my invention shown in Figs. 1 to 4, 9 is a box or receptacle preferably made of sheet steel within which is mounted a suitable insulating base block 10 which may or may not carry the usual fuse plugs 11—12. 14—15—16—17 are contact terminals designed to be engaged by the switch blades 18—19—20 and 21, respectively. These switch blades are mounted 45 upon a suitable block or insulating head 22, and the insulating head is yieldingly connected to the cover 23 of the receptacle by means of suitable springs, such as indicated at 24—24. 25 is the lost motion stop which has 50 a head 26 at its free end and is provided with a swivel connection 27 with the cover

23 at its other end. The insulating block 22 has a counterbore extending through the same as indicated in section, Fig. 2, in which the lost motion stop stands. 28 is a buffer, for example, a rubber washer. The normal tendency of the springs 24—24 is to hold the block 22 and the switch blades carried thereby in the position shown in Figs. 1 and 2, that is to say, with the insulating block 22 bearing against the buffer 28. Utilizing the hinge cover 23 of the receptacle as a handle or lever, the same may be swung down so as to close the box and simultaneously cause the switch blade to electrically connect with the switch terminals 14 to 17. At such a time the parts will stand in the position indicated in Fig. 3. When it is desired to open the circuit, the box cover 23 is swung open, and the first partial movement thereof, simply 70 puts the springs 24—24 under tension. Continued movement of the box cover will cause the head 26 of the lost motion stop to engage in the bottom of the counter-bore in the insulating block 22, whereby the further 75 opening movement of the box cover will 80 positively withdraw the switch blades from their respective terminals or contacts. As soon as the friction is light enough the springs 24—24 will operate to complete the 85 circuit breaking act by quickly pulling the switch blades out of contact with their respective terminals, so as to avoid arcing. It will be noted that the switch is of the double 90 break type.

One of the many advantages in the combination of elements illustrated in Figs. 1 to 4, resides in the fact that the fuses cannot be tampered with, renewed or removed while the switch is on, since the switch handle, 95 namely the box cover, must be open before access can be had to the fuses. Again, by said arrangement, all of the various parts of an entrance switch for house lighting service may be arranged in exceedingly compact and safe form.

It will be understood that various changes may be made in the various parts and combination of parts herein disclosed without departing from the spirit and scope of my 105 invention.

What I claim is:

1. In a switch of the character set forth, a box and a movable cover therefor, an insulating base within the box, an insulating 110 base at the underside of the cover, co-operating switch contacts on the respective bases,

2
one of said insulating bases being movable relative to the part by which it is carried, a spring connection between said insulating base and the part by which it is carried to thereby enable the cover to have a limited movement without separating the contacts and a positive lost-motion connection between said movable base member and the part by which it is carried, limiting the extent of such free movement of said insulating base member on the part by which it is carried and insuring a snapping apart of the switch contacts when the cover is opened.

2. An inclosed switch construction comprising a box having a movable cover, relatively stationary switch contacts mounted in

the box, an insulating base, a relatively flat spring secured to the under side of the cover and to said base to thereby yieldingly confine said insulating base to the under side of the cover, a headed stud projecting from the under side of the cover, said insulating base having a passage for said stud and a stop shoulder engageable by said head to limit the movement of the insulating base away from the cover and contacts on said yieldingly supported but positively stopped insulating base for engagement with the contacts in the box and insulated from the cover by said insulating base.

CLARENCE D. PLATT.
